UNITED STATES PATENT OFFICE.

JOSEPH R. BROOKS, OF CEDAR RAPIDS, IOWA, ASSIGNOR OF ONE-HALF TO M. FORD, OF CEDAR RAPIDS, IOWA.

GRAIN-DRIER.

No. 861,354.

Specification of Letters Patent.

Patented July 30, 1907.

Application filed September 26, 1906. Serial No. 336,232.

To all whom it may concern:

Be it known that I, JOSEPH R. BROOKS, a citizen of the United States, residing at Cedar Rapids, in the county of Linn and State of Iowa, have invented certain new and useful Improvements in Grain-Driers, of which the following is a specification.

The object of this invention is to produce a grain-drier of a type that may be safely used in buildings not of fireproof construction, and adapted to dry grain 10 very uniformly and thoroughly, preparatory to grinding or hulling.

In the preparation of grain for milling, particularly oats, barley, etc., one of the essential, but difficult operations is to dry it perfectly. If all the grain is 15 fully dried, some of the grains are likely to be scorched, and this is especially true where the grain is dried in pans, or in other types of driers in which there is a considerable body of grain exposed to the high heat of a metal surface, and the grains in contact with such 20 surface are not sufficiently agitated, and so are burned, while the rest of the grain is only dried, more or less imperfectly. Of course this produces an inferior grade of grain, it being impracticable to eliminate the scorched kernels. It is with a view to overcoming 25 these difficulties that the subject matter of this application has been devised, and the same is fully disclosed in the description and claims following, reference being had to the accompanying drawings, in which—

30 Figure 1 is a side view of a drier embodying my improvements. Fig. 2 is the same as seen from the right hand end of Fig. 1. Fig. 3 is a section on the line *a b* of Fig. 5, looking to the left. Fig. 4 is a section on the line *c d*, looking in the same direction. 35 Fig. 5 is a side view, partly in section in different planes, showing one of the complete units, of which twelve are illustrated in Fig. 2, this single drier being broken in the middle, however, the better to show the essential features of the invention. Fig. 6 illustrates diagrammatically a drier on the same principle, but using furnace heat instead of electric heating coils. Fig. 7 is a central section of the drive for the 40 drying cylinder, and a fragment of the cylinder.

The invention is most completely illustrated in 45 Fig. 5, but for large productiveness is best organized in gangs or batteries, as shown in Figs. 1 and 2. This may be easily done by adding unit to unit, vertically or horizontally, or in both directions, as will appear from the description following, and by reference to 50 the drawings.

Referring now to Fig. 3, the drier is shown mounted in a frame 1, forming the base section. This is provided with lateral arms 2 by which it may be bolted to a superior unit 3, having similar arms. From the 55 ends of these arms depend lugs 4, by which the units may be bolted together in horizontal order, as clearly

shown in Fig. 2. These frame castings are formed with annular flanges 5 to take the ends of the drier jacket 6 on their inner sides. The similar outer flanges of alternate castings take hoods 7, to the bottoms of which are connected pipes or spouts 8 leading to a drier drum, to be described presently. From the upper portions of these hoods run a series of converging pipes 9 leading to an exhaust fan 10, the purpose of these pipes and fan being to carry off the steam 65 and vapor arising from the damp grain in the process of drying.

The internal mechanism of the drier is best shown in Fig. 5. The jacket 6, already referred to, is for the purpose of confining and conserving the heat within 70 and in close proximity to the driers. As herein illustrated it comprises an inner and an outer shell of sheet metal and an interposed packing of some suitable non-conductor of heat, such as asbestos or mineral wool. The cylindrical jacket is held in place by 75 rods 11 (Fig. 1).

The preferred method of imparting heat to the drier is by electric coils 12 mounted on suitable earthen or porcelain tubes 13, and mounted in gangs between metal rings 14 of practically the outer diameter of the 80 inside of the jacket. The rings and tubes are all held in place by rods 15, as shown. The terminals of the coils pass out through the jacket, and are suitably connected up electrically in the conduits 16 and junction boxes 17, an illustrative set of which is shown in Fig. 1, it being understood that each unit of the drier is similarly equipped. Current is derived from any suitable source of electrical energy, not shown.

Inside the jacket and the circle of heating coils is mounted the revoluble grain conveyer, through which the grain passes while exposed to the surrounding heat. The conveyer comprises a cylinder 18 and an internal spiral 19 attached to it. At intervals, between the wings of the spiral, cleats 20 are attached to the inside of the cylinder. These cleats render it impossible for any of the grain to remain long in one position, and prevent any tendency of the grain to seek the bottom of the cylinder and simply slide as it revolves. Extending from wing to wing of the spiral, the cleats carry every grain up from the bottom, and as the mass moves from end to end of the cylinder every grain is repeatedly lifted from the position of greater or less exposure to scorching, carried part way up the rising side of the cylinder, and overturned. This thorough agitation of the grain is calculated to secure the greatest possible uniformity in drying, and prevent any scorching, results which are of great importance in the preparation of many cereals. The conveyers are in the nature of drums, with closed heads, open only at 21 to admit the grain, and at 22 to discharge it, as shown. They are 110 preferably provided with a perforated central tube 23 to facilitate the escape of steam and vapor from the dry-

ing grain. A slow rotation is imparted to the drums by means of geared rings attached to them near each end, and pinions meshing therewith. Each ring is toothed at 24, and adjacent to the teeth, with its periphery coinciding with the pitch line of the gear, is a smooth surfaced bearing portion 26. This rests on the corresponding portion of the pinion, 27, which is toothed at 25 to engage with the large gear. The shafts 28 carrying the pinions are mounted in bearings 29 bolted to suitable lugs 30 formed on the frame castings. The shafts are provided with sprockets 31 at the outer ends, and are driven by sprocket chains 32, in the simple manner shown in Figs. 1 and 2.

In Fig. 7 the track-ring and gear-ring are shown integral. The ring is made large enough inside to clear the rivet-heads of the cylinder, and shimmed up with space-blocks 33. The drum is best formed in a spiral, conforming to the pitch of the spiral inside.

Fig. 6 represents a battery of driers inclosed in a rectangular, non-conducting casing 34, of substantially the same construction as the jacket already described. Horizontal partitions 35, of the same material, are arranged in alternate order with respect to regulating dampers 36. Heat from any suitable source is drawn through the drier by a suction fan 37.

Aside from the advantages already noted, it is evident that the close jacketing of the drier tends to effect the highest economy in the consumption of fuel, and that the general construction is such as to make the apparatus practically safe in a building of almost any sort. It will also be evident that the amount of heat may be very nicely and accurately regulated to meet all conditions, particularly in the case of the preferred type shown, using electric heating apparatus.

In addition to the heat-retaining jacket already described, annular rings 38 are provided to close the an-

nular openings at each end. These are of substantially the same construction as the jacket.

It will be noted that the arrangement of the stack of driers is alternative, the discharging end of one conveyor being just below the receiving end of the one above. The conveyers preferably all revolve in the same direction, and in this case the spirals of alternate conveyers are pitched in opposite directions, as indicated by Figs. 4 and 5.

Having thus described my invention, what I claim as new and desire to secure by Letters Patent, is:

1. In an organized grain-drier, the combination of a group of drying units, each of which comprises a revolving conveyer through which the grain passes, a non-conducting shell inclosing the conveyer, and a frame adapted to support both the conveyer and the shell, the frames of the several units being adapted for indefinite extension of the system by bolting to each other laterally or vertically.

2. In a grain-drier, the combination of a revolving conveyer, through which the grain passes in drying, stationary inclosing shell of non-conducting material surrounding the conveyer, and electrical heating coils mounted between the conveyer and the shell, and adapted for connection with a source of electrical energy, substantially as described.

3. In a grain-drier, the combination of a series of superimposed grain-drying units, each comprising a grain-conveyer through which the grain passes from end to end, a heat-retaining inclosure for each conveyer, means for revolving the conveyers, and for imparting heat to said inclosures, grain-pipes leading from the discharging end of one conveyer to the receiving end of the one next lower, alternately, pipes to carry the steam and vapor from said conveyer and inclosures, and a suction fan therefor, substantially as set forth.

In testimony whereof I affix my signature in presence of two witnesses.

JOSEPH R. BROOKS.
